UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,555, dated January 7, 1890.

Application filed December 9, 1889. Serial No. 333,153. Term of patent 3½ years.

To all whom it may concern.:

Be it known that I, WILLIAM K. BENEDICT, of the city and county of New York, in the State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular in the ground plan, and comprises a first and second story and an attic story. The whole is surmounted by gable roofs. The front of the house A is illustrated as having arranged near one corner a porch B, to which steps a lead. At one side of the porch B is an octagonally-shaped bay C. The end of the house in the first story has a sub-

stantially flat exterior. Near the rear there is 25 illustrated a porch D, to which a flight of steps d leads. One of the slopes of the roof extends downwardly to the top of the first story, and consoles e are arranged between the eaves of such portion of the roof and the tops of pillars e', which form portions of the porch. Upon this slope of the roof E is shown a dormer-window F. At one side of the dormer-window F is another and considerably larger dormer G. The dormer G overhangs the bay 35 C, and other consoles f are between it and the bay C. The rear slope of the gable roof E is considerably shorter than the front slope. The second and attic stories of the residence upon the end are shown as substantially flat. 40

What I claim is—

The design for the exterior of a residence, substantially as herein shown and described.

WILLIAM K. BENEDICT.
